UNITED STATES PATENT OFFICE.

AUGUST FABER, OF NEW YORK, N. Y.

DIRIGIBLE AIRSHIP.

Application filed June 24, 1927. Serial No. 201,166.

This invention relates to airships and more particularly to airships of the dirigible type where the weight of the structure is mainly or totally supported by a lighter than air gas.

The main object of the present invention is to provide a novel and improved dirigible airship of the class where lighter than air gas containers are used to provide the necessary lifting power, which is designed so as to offer the minimum of resistance to transversely directed air currents, at the same time possessing great stability and speed.

Another object of the invention is to provide a dirigible airship of a novel and improved design, the buoyancy of which is provided by gas containers having relatively large supporting surfaces adding to the stability of the structure as a whole, and also assisting the lifting action of the gas.

A further object is to provide a novel type of airship possessed of great stability due to the relation existing between its center of propulsion and its center of pressure, designed so as to offer a minimum of resistance to the air both in a longitudinal and in a transversal sense.

Other objects and advantages of the present invention will more fully appear as the description proceeds and will be set forth and claimed in the appended claims.

Airships of the dirigible type generally comprise a gas bag or container from which is suspended a car or frame containing the motors and the quarters for the crew as well as the supply of fuel. As a general rule, the lifting power is entirely provided by the gas contained within the gas container, and as a consequence the container generally has considerable bulk and finds a proportional resistance in the air tending to oppose its progress.

In airships of the type more generally used, the gas container is cigar shaped and has quite a considerable diameter for the greater portion of its length intermediate of its tips. Due to this design, airships have often become unmanageable when exposed to strong winds and storms and their navigation constitutes a serious problem even in the presence of winds of a moderate intensity, especially when the wind is directed transversely of the body of the airship.

Another factor which greatly affects the stability of these structures is the relative

arrangement of the center of propulsion and the center of pressure. As a general rule, the propellers are carried by the car and are approximately in line with the center of gravity of the structure. Due to the fact that the maximum weight is concentrated in the car, the center of gravity is much lower than the longitudinal axis of the gas container; on the other hand, the bulk of the car as compared to that of the gas container is relatively small and therefore the center of pressure is considerably higher than the center of gravity.

Due to these conditions, a tilting moment generally occurs between the center of propulsion and the center of pressure, tending to offset the horizontal alignment of the airship, and this tends to dispose the bulk of the gas container at an angle which does not coincide with its position of least resistance.

The car portion of the structure furthermore, usually comprises a frame having substantially vertical sides and materially increases the amount of surface exposed to the action of lateral air currents, further affecting the stability of the structure.

The airship forming the object of the present invention is practically free of these undesirable features, due to the improved arrangement of its various parts. By virtue of its construction, the lateral resistance of the structure has been reduced to a minimum, so that not only is it easier for the airship to successfully weather storms of high intensity, but it is also possible for it to steadily maintain its predetermined course.

Furthermore, my improved construction causes a lowering of the center of pressure as compared with that of an airship of the ordinary type, at the same time permitting the center of propulsion to be raised; and in this manner practically evenly balanced conditions may be realized causing the airship to naturally assume and maintain the horizontal position in flight which corresponds to a minimum air resistance.

Another feature of this construction is that the airship is composed of three stream line shaped bodies having smooth surfaces and sloping sides and ends offering comparatively little resistance to the air through which the airship travels; so that for a given expenditure of power it is possible to attain a relatively high rate of speed.

The novel features and advantages of my

invention will be better understood by referring to the accompanying drawings, in which:

Fig. 1 is a side view in elevation of the airship;

Fig. 2 is a rear view in elevation of the same;

Fig. 3 is a fragmentary front view in elevation of the same;

Fig. 4 is a plan view of the same.

As the drawings show, my improved airship consists of three fish shaped bodies 10, 11, 12, the longitudinal axes of which are disposed in an inverted practically triangular arrangement; the two bodies 10, 11, being arranged side by side in parallel arrangement along the same horizontal plane, and the third body 12, being arranged centrally thereof in a lower horizontal plane.

These three bodies are each composed of two relatively shallow convex surfaces, sloping both in a lateral and in a longitudinal direction at both ends, joined along their edges. Said bodies are furthermore, arranged with their maximum width in a horizontal plane so as to offer a relatively small resistance to lateral air currents in view of their limited height.

The three bodies mentioned are connected to one another by means of two outer series of brace members 13, 14, and two inner series of brace members 15, 16, as well as by reinforcing end braces 17, 18; all these brace members forming a relatively light but rigid structure which is further reinforced by horizontal braces 19, extending between the two upper bodies 10, 11.

The two upper bodies are utilized as gas containers, while the central lower body 12 constitutes the car portion of the airship where the motors and fuel supply and the living quarters for the crew are located. If desired, a certain portion of central body 12 may also be devoted to carrying an additional supply of gas in order to increase the buoyancy of the structure.

The front end 20 of body 12 is preferably provided with a raised portion or nose 21, forming a pilot room where the steering and navigating devices and instruments may be located. 22 designates the vertical rudder and 23, 24, the horizontal rudders which may be controlled in any suitable manner.

It will be observed that due to the triangular arrangement of the three bodies, the center of pressure is located at a point intermediate between the upper and the lower bodies, so that the propellers 25, 26, may be conveniently located laterally of and above the rear end of body 12, so as to be practically in alignment with the said center of pressure, or at no great distance therefrom.

The form of the three bodies of which the structure is composed, which in each case resembles that of a fish disposed in a hori-

zontal plane, causes the finished structure to offer very little resistance to the air both in a lateral and longitudinal sense, due to the stream line and smoothness of its surfaces; this, coupled with the fact that the structure is evenly balanced in a horizontal direction, produces conditions of minimum resistance to the longitudinal travel of the airship.

It will be further observed that in a lateral sense, the two superimposed but spaced body thicknesses are relatively shallow and also have gradually sloping surfaces, offering comparatively little resistance to the wind. In addition to this, it will be observed that the vertical spacing of the upper set of bodies and the lower body permits air currents to freely pass therebetween, and to enhance the stability of the structure by exerting antagonistic actions against the surfaces of the lower and upper bodies.

Due to the peculiar arrangement of the central lower body 12 having its upper surface 27 bulging upwardly at 28 in relation to the inner longitudinal portions of bodies 10, 11, the lower surfaces of which 29, 30 slope upwardly as at 31, 32, towards the center of the structure, a sinuous passage 33 is provided between said bodies running from one side to the other of the structure, which closely resembles a Venturi throat; so that the air can travel at relatively high velocity through the structure without engendering excessive frictional surface losses.

Another advantage resulting from the arrangement described, is the relatively large supporting surface provided by the three horizontally disposed bodies. Such a surface provides a parachute or cushioning effect which goes to increase the buoyancy of the structure and which materially assists the same in maintaining its normal horizontal position.

The structure described is preferably of the rigid type, but if desired, a semi-rigid construction permitting some displacement of the lower body in relation to the upper bodies may also be adopted. Such a result may be obtained with comparative ease by providing a rigid bracing structure between the two upper bodies such as represented by braces 19 and providing flexible connections between the upper bodies and the lower body in place of rigid braces 13, 14, 15, 16, 17, 18.

My invention is not limited to any particular system of gas container or body structure, it being understood that the three units of which the airship is composed may be made of any suitable material and may be built in any manner conforming with modern engineering practice; since the essence of the invention resides in the general arrangement and form of said units, principally in so far as the reaction of the air against their surfaces is concerned, and in so far as their mutual arrangement affects

the buoyancy and stability of the structure.

It is obvious that additional plane surfaces may be employed if desired, in order to assist the lifting power due to the gas carried in the containers.

This and other changes may be introduced in the embodiments of my invention without substantially departing from the inventive idea, the drawings being understood 10 as being intended for illustrative purposes only and not in a limiting sense.

I accordingly reserve to myself the right to carry my invention into practice in any way or manner which may enter, fairly, into 15 the scope of the appended claims.

I claim:

1. In an airship, the combination of a gas container and a body depending and vertically spaced therefrom, said body consisting of a longitudinally elongated shell, 20 composed of two relatively shallow and wide convex sections having sloping ends, placed edge to edge, forming a body offering a relatively small resistance to the air in a lateral rather than in a vertical sense.

2. In an airship, the combination of two elongated gas containers longitudinally directed in parallel spaced arrangement on the same horizontal plane and a central body 30 vertically spaced therefrom, depending from said gas containers, said body being in the form of an elongated shell, comprising two relatively shallow and wide convex sections placed edge to edge, and propelling means carried by said body.

3. In an airship, the combination of two elongated gas containers longitudinally directed in parallel spaced arrangement on the same horizontal plane, said gas containers 40 being each formed by two relatively shallow and wide convex sections placed edge to edge, a body centrally located in relation to said containers and vertically spaced therefrom, said body being in the form of a relatively shallow and wide elongated shell comprising a lower and an upper section placed edge to edge, said upper shell having a convex surface, and a skeleton structure connecting said two gas containers to each 50 other and to said body.

4. In an airship, the combination of two elongated gas containers longitudinally directed in parallel spaced arrangement on the same horizontal plane, said gas containers 55 being each formed by two relatively shallow and wide convex sections placed edge to edge, a body centrally located in relation to said containers and vertically spaced therefrom, said body being in the form of

an elongated shell comprising two relatively shallow and wide convex sections placed edge to edge and a skeleton structure connecting said two gas containers to each other and to said body.

5. In an airship, the combination of two elongated gas containers longitudinally directed in parallel spaced arrangement on the same horizontal plane, said gas containers being each formed by two relatively shallow and wide convex sections placed edge to edge, a body centrally located in relation to said containers and vertically spaced therefrom, said body being in the form of an elongated shell comprising two relatively shallow and wide convex sections placed edge to edge, a skeleton structure connecting said two gas containers to each other and to said body, propelling means carried by said body, and steering means for the resulting structure.

6. In an airship, the combination of two elongated gas containers longitudinally directed in parallel spaced arrangement on the same horizontal plane, said gas containers being each formed by two relatively shallow and wide convex sections placed edge to edge, a body centrally located in relation to said containers and vertically spaced therefrom, said body being in the form of an elongated shell comprising two relatively shallow and wide convex sections, placed edge to edge, a skeleton structure connecting said two gas containers to each other and to said body, and propelling means for the resulting structure symmetrically located in the vertical space separating said gas containers from said body.

7. In an airship, the combination of two elongated gas containers longitudinally directed in parallel spaced arrangement on the same horizontal plane, said gas containers being each formed by two relatively shallow and wide convex sections placed edge to edge, a body centrally located in relation to said containers and vertically spaced therefrom, said body being in the form of an elongated shell comprising two relatively shallow and wide convex sections, placed edge to edge, a skeleton structure connecting said two gas containers to each other and to said body, propelling means for the resulting structure symmetrically located in the vertical space separating said gas containers from said body, and steering means interposed between said containers and said body adjacent the rear ends thereof.

AUGUST FABER.
